VIBRATING CONVEYORS

Inaco Comensoli and Luigi Mansini, Vancouver, British Columbia, Canada, assignors of twenty percent to John Stewart

Application October 7, 1957, Serial No. 688,472

3 Claims. (Cl. 198—220)

Our invention relates to improvements in vibrating conveyors for conveying comminuted material through closed conduits.

The object of the invention is to provide a means of handling material continuously without creating dust, but to convey said material horizontally or up inclines of up to thirty degrees above the horizontal dependent upon the nature of the material carried.

A further object is to provide a conveyor which will convey comminuted material from point to point with great economy of motivating power.

The device is illustrated in the accompanying drawings, in which:

Figure 1 is a longitudinal elevation of the invention set to deliver material horizontally.

Figure 2 is an enlarged fractional elevation showing the disposition of the driving motor.

Figure 3 is a section taken on the line 3—3 of Figure 2.

Figure 4 is a section taken on the line 4—4 of Figure 3 and showing a typical connecting rod disposed between 35 the two conduit pipes.

Figure 5 is a plan of the pipe mounting.

Figure 6 is an enlarged section taken on the line 6—6 of Figure 1 and showing the spring mounting box.

Figure 7 is a detailed section of the spring mounting box taken on the line 7—7 of Figure 6.

In the drawings like characters of reference indicate corresponding parts in each figure.

The numeral 1 indicates a base from which are erected a plurality of spaced pairs of side plates 3. Each pair of plates is fitted on its outer face with upper and lower spring boxes 4 and 5 respectively. The spring boxes are preferably circular as shown particularly in Figure 7 and are provided with adjustably mounted eye bolts 7 to each of which a tension spring 8 is connected. The springs 8 and the eye bolts are disposed radially within the boxes and a bearing 10 is connected to the inner free ends of all the springs.

Horizontally mounted between the side plates 3 are upper and lower pipes 12 and 14 having longitudinally spaced pairs of trunnions 15 which may be fitted to sleeves 16 surrounding said pipes. The trunnions extend through apertures 17 in the plates 3 and are supported in the bearings 10. The apertures 17, as shown in Figure 6 only, are substantially three times the diameter of the trunnions so that said trunnions are free to oscillate within the openings during vibration of the pipes 12 and 14. It will be noticed that the trunnions of the upper pipe 12 are disposed in the direction of the material being conveyed forwardly of the trunnions on the pipe 14. The pipes 12 and 14 are separately connected by means of resilient sleeves 18 to pipe bends 19 and by further resilient sleeves 20 to a feed hopper 21, or any other source of material to be conveyed.

A platform 22 is erected on legs 23 above the pipes 12 and 14 and adjacent said platform a transverse sleeve 25 is fitted to the upper pipe 12 to support a horizontal

2

shaft 27. The shaft 27 is journaled in a bearing 28 and is belt and pulley driven at high speed from a motor 29 mounted upon the platform 22. The shaft 27 is provided adjacent each end with an eccentric 30 which engages the upper end of a connecting rod 32. It will be obvious that the springs 8 in the spring boxes 4 and 5 will be adjusted to normally support the pipes 12 and 14 when the axes of the eccentrics 30 are lying in the same horizontal plane as the shaft 27.

10 Each connecting rod 32 consists of an upper member 33 and a slightly oscillatory lower member 34. The lower member 34 is connected to upper member 33 by a pivot pin 35 and the lower end of said member 34 is connected by one or more bolts 37 either to a sleeve 16 or directly to the pipe 14. The lower member 34 is cushioned against swinging in a vertical plane parallel to the axes of the pipes by two compression springs 39 disposed on opposite sides of the pivot pin 35. The springs 39 will exert pressure against each other, but which 20 will allow a certain lagging movement of the pipe 14 relative to the pipe 12.

Where the pipes 12 and 14 are of substantial length or the material to be conveyed is heavy, supplementary supporting arms 41 may be provided. These arms are 25 particularly illustrated in Figure 6 and are provided with end and central apertures 42 and 43 respectively, all of which are fitted with rubber bushings 45 and 46. The bushings 45 of the arms are mounted on the trunnions 15 and the bushings 46 are mounted on center pins 48 which extend inwardly from the side plates 3. The bushings 45 and 46 permit the arms 41 to move to a very slight extent relative to the side plates 3 and the trunnions 15, but it has been found that the movement of the arms is mainly a rocking motion about the center pins 48. The arms 41 and their associated parts form resilient couplers 50 which serve to maintain the upper and lower pipes 12 and 14 parallel to each other throughout their length, thereby making the magnitude of the vibrations of all portions of the length of said pipes to 35 be constant and the oscillatory urge of material being conveyed to be constant also at every part of their length.

With material entering the pipes 12 and 14 from the hopper 21 and the motor 29 running in the direction shown in Figures 1 and 2 a given point of the upper pipe will swing in an anticlockwise direction about an ovate orbit so that the material in the pipe will be thrown upwardly and rearwardly while the springs 8 in the spring boxes supporting the upper pipe are striving to counteract said movement. The movement of the pipe 12 on its over stroke or along the upper part of its orbit will initiate an upward and leftwards movement in the lower pipe 14, but this movement will be retarded out of phase with the first-named movement due to the rocking of the lower members 34 about their pivot pins 35. Since the oscillation cycles of the two pipes 12 and 14 are out of phase, the load on the motor is substantially constant after the said pipes have become filled to their normal operating condition.

What we claim as our invention is:

60 1. A vibratory conveyor comprising a plurality of standards spaced apart, each of said standards having two side members and each of said side members being provided with two sets of radially mounted springs, the springs of each set being connected to a pipe supporting bearing, a pair of parallel pipes each having trunnions, each trunnion being seated in the supporting bearing of a set of springs whereby each of the pipes may oscillate with respect to and out of phase with the other of said pipes, a driven shaft carried by and mounted for rotation on one of said pipes, said shaft 65 having an eccentric rotatable therewith, a connecting rod

connected with the eccentric to be moved thereby, said connecting rod being connected to the other pipe to oscillate it as the eccentric is rotated, resilient couplers connecting the pipes at intervals of their length and means for rotating the shaft.

2. In a vibratory conveyor as claimed in claim 1, wherein each resilient coupler is resiliently and pivotally mounted upon a fixed part of the conveyor and is connected at its ends to the pipes.

3. In a vibratory conveyor as claimed in claim 2, 10

wherein the connection of the resilient couplers to the pipes is through the pipe trunnions.
